UNITED STATES PATENT OFFICE.

GUY L. KENNEDY, OF LOS ANGELES, CALIFORNIA, ASSIGNOR, BY MESNE ASSIGNMENTS,
TO AUTO BETTERMENT CORPORATION, OF NEWARK, NEW JERSEY, A CORPORATION
OF DELAWARE

CARBURETER.

1,260,980.

Specification of Letters Patent. Patented Mar. 26, 1918.

Application filed March 29, 1916. Serial No. 87,592.

To all whom it may concern:

Be it known that I, GUY L. KENNEDY, a citizen of the United States, residing at Los Angeles, in the county of Los Angeles and 5 State of California, have invented a new and useful Carbureter, of which the following is a specification.

This invention relates to devices of the character designed to produce gas from 10 liquid hydrocarbons and mix said gas and a suitable volume of air together to make an ignitable mixture for producing heat, light or power, the volume of the mixture being proportional to the draft of air through the device, said draft being produced for power purposes, for instance, by suction of the engine to which the device may be attached.

An object of this invention is to produce 20 a device of this character which is simple to manufacture and reliable in operation.

Another object is to produce a device of this character in which the throttle valve and fuel valve are simultaneously controlled.

Another object is to make provision for 25 very delicate adjustment of the degree of opening of the fuel valve.

Another object is to so construct the cam for limiting the movement of the needle valve as to permit of adjustment of the cam 30 at different portions thereof, so as to enable the operator to make the proper gaseous mixture for all speeds of the engine to which the device may be attached and so as to obtain maximum speed and power with a minimum 35 consumption of fuel.

Other objects and advantages may appear in the subjoined detail description.

The accompanying drawings illustrate the invention:

40 Figure 1 is an elevation of a carbureter built in accordance with this invention, the arcuate cam member being partly shown in section for clearness of illustration.

Fig. 2 is a vertical sectional elevation on 45 line indicated by x^2-x^2 , Fig. 1.

Fig. 3 is a plan section on line indicated by x^3-x^3 , Figs. 1 and 2.

50 Fig. 4 is an enlarged elevation of the valve plug and cam parts and their adjusting means, the parts being in the partly open position.

There is provided an L-shaped passage 1 having a contracted cylindrical throat 2 and terminating above the contracted throat in

an upwardly expanding circular mouth 3. 55 The passage 1 extends through the peripheral wall of a cylindrical carbureting chamber 4 with which it may be integral, if desired, as shown in the drawings.

The L-shaped passage 1 is provided in 60 axial alignment with the mouth 3 with a nipple 5 through which passes a vertical fuel supply tube 6 terminating at its top in a nozzle of somewhat greater inside diameter than the inside diameter of that portion 65 of the tube below the nozzle, said tube being provided at the lower end of the nozzle with a valve seat 7 adapted to be engaged by a needle valve 8 so that the passage of fuel through the tube 6 from a suitable source of 70 supply, not shown, may be controlled by appropriate operation of said needle valve. The upper end of the stem 9 of the needle valve 8 projects above the rim of the mouth 3 and is provided with a semispherical or 75 saucer-shaped fuel spreading air valve 10 of substantially the same curvature as the curvature of the inner surface of the mouth 3. The valve 10 rests close to but is slightly spaced from the mouth 3 when 80 the needle valve 8 is on its seat 7. Thus there is always an annular passage of comparatively small cross sectional area between the valve 10 and mouth 3, the cross sectional area of said passage being increased and diminished by raising and lowering of the valve 10. 85

The upper end of the valve stem 9 is adjustably limited by an adjustable abutment formed by the inner end of a lever 11 which is pivoted at 12 to a bracket 13 fastened to 90 the top of the carbureting chamber 4. The lever 11 has its outer end projecting through a small slot 14 in the wall of the carbureting chamber 4 and the outer projecting end of said lever is adjustably limited in its 95 downward movement by an adjustable cam face 15 formed of spring strip metal. The ends of the cam face 15 are loosely bent around the ends of an arcuate cam-conveying member 16 which is provided with a 100 number of adjusting screws 17 from end to end thereof, said screws bearing against the under side of the cam strip so that by adjusting said screws the contour of curvature of the cam strip may be changed from end 105 to end or at points intermediate of all ends.

The arcuate member 16 is at one end of

one arm 18 of a lever, the other arm of said lever forming a plate valve 19 at the inlet end of the air passage 1 adapted to control the passage of air from the atmosphere into said air passage, there being an air port 19' opening through the valve 19 so that even when said valve is closed a small volume of air can pass into the passage 1. The lever 18, 19 is pivoted at 20 to the carbureting chamber 4 and said lever is operated by any suitable means, there being provided for this purpose a boss 21 on the valve 19 and an operating rod 22 engaging said boss.

The tube 6 is screw-threaded through a bushing 23 which in turn is screw-threaded into the head 24 of a homogenizing chamber which comprises besides said head a cylindrical body 25 that is screw-threaded at its lower end into said head 24 and is screw-threaded at its upper end into the carbureting chamber 4 below the air passage 1, said homogenizing chamber surrounding that portion of the tube 6 extending from the nipple 5 to the head 24.

25. The homogenizing chamber is provided with a tube 26 having its lower end spaced apart from the head 24 and having its upper end expanded to form a conical mixture inlet 27 which has its rim fitting against the inside of the cylindrical body 25. The tube 26 is provided inside and outside with a woven fabric mantle 28 which may be of cloth or other suitable material. The tube 6 is provided on its outside with a mantle 29 of woven fabric the same as the mantle 28, said mantles serving to catch any un-gasified or unvolatilized liquid particles passing from the mixture chamber 4 so as to attenuate said liquid particles to the gasification degree ere they can pass from the homogenizing chamber through an outlet 30 near the upper end of the homogenizing chamber. The outlet 30 may be connected to any gas consuming device as, for instance, an internal combustion engine, the suction of said engine producing the draft necessary to lift the valves 8 and 10. The necessary draft may be produced by a blower as disclosed in my copending application for patent for apparatus for producing a combustible gaseous mixture, filed February 19, 1916, Serial No. 79,313.

In practice, assuming that the outlet pipe 30 is attached to a gas consuming device such, for instance, as the intake of an internal combustion engine, and assuming that the tube 6 is connected to a suitable source of liquid hydrocarbon supply, the suction produced by the operation of said engine will 55 operate to lift the valve 10 as high as the strength of said suction will lift it or as high as the lever 11 will permit and air will pass through the port 19' into the air passage 1, thence through the neck 2 and annular pas-

sage *a* and out of the mouth 3 into the carbureting chamber 4. Lifting of the valve 10 raises the valve 8 from its seat to admit liquid hydrocarbon from the tube 6 and bubbles of gas are formed around the rim of the valve 10; but a large proportion of the fuel admitted by the valve 8 is still in the form of a vapor or fog. The hydrocarbons, whether gaseous or liquid, pass from the mouth 3 downward through the tube 26 to the lower end thereof and thence upward between the tube 26 and cylindrical member 25 to the outlet tube 30 through which they flow to the gas consuming device, not shown.

It is noted that in the downward passage of the hydrocarbon and air through the carbureting chamber 4 to the upper end of the cylindrical member 25, any liquid particles of hydrocarbon in the mixture will impinge on the mantles 28 and 29, and owing to the attenuating effect of the mantles on the liquid particles, said liquid particles will be gasified so that the mixture passing from the gasifying chamber will be nothing but a mixture containing hydrocarbon gas and atmospheric gases which together form an ignitable gaseous mixture capable of being burned or exploded in the gas-consuming device.

With the valve 19 closed so that the only air admitted to the device is through the port 19', and with the cam strip 15 adjusted so that but a minute quantity of liquid hydrocarbon will be admitted by the valve 8 to the nozzle, only a small volume of gaseous mixture of a constant or uniform quality will be produced by the device and will pass to the engine thus causing said engine to run at comparatively low speed. When higher speed of the engine is desired, the operating rod 22 will be moved to open the valve 19 and swing the arcuate member 16 so as to move the cam strip 15 into such position as to bring a lower point thereof adjacent the outer end of the lever 11, thus permitting more liquid hydrocarbon to be sucked from the tube 6. The increased volume of gaseous mixture thereupon resulting will pass to the engine and of course, as is readily understood, will produce greater rotative speed thereof in a manner well understood in the art.

When the device is first installed in connection with an engine, perfect adjustments thereof for the most economical use of the hydrocarbon fuel is easily effected because, with the valve 19 closed, the appropriate screw 17 will be adjusted to reduce the quantity of hydrocarbon admitted to the nozzle to the minimum capable of maintaining idling speed of the engine. Then the valve 19 will be opened to the maximum or to any desired extent and the screw 17 adjacent the outer end of the lever 11 will be adjusted so

as to cut down the amount of fuel to the minimum requisite to run the engine at the maximum speed.

It is seen that by the construction hereinbefore described, that the adjustments just noted may be made for various speeds intermediate of the low and high speeds of the engine so that, rather than providing a uniform mixture at all engine speeds, the mixture may be made richer at low engine speeds and thinner or leaner at high engine speeds in exact accordance with the demands of the best engine practice.

It is noted that the arcuate member 16 and lever arm 18 form a member that is in adjustable relation to the valve 19 and that the pivot 20 is in the form of a shouldered thumb screw or stud. The arm 18 and valve 19 are held against relative rotative movement by a spring member 31 through which the thumb screw 20 passes, one end of said spring member being bent into engagement with a hole 32 in the arm 18 and the other end of said spring member being bent into engagement with any one of a series of holes 33. When the thumb screw 20 is tightened up it holds the spring member 31 in engagement with the hole 32 and with one of the holes 33.

30 To change the proportions of air and hydrocarbon without changing the contour of the cam strip 15 all that is necessary is to move the spring member 31 to the right or left relative to the valve 19 in Fig. 4 so as 35 to bring a different portion of the cam strip adjacent the outer end of the lever 11 for any given position of said valve relative to the inlet end of the air passage 1.

The foregoing will enable those skilled in 40 the art to which this invention appertains to make and use said invention.

I claim:

1. In combination, a carbureting chamber, an air passage in the carbureting chamber, 45 a fuel supply tube terminating in the air passage, a draft-operated valve for the air passage, a needle valve for the fuel supply tube operative by movement of said draft-operated valve, another valve for the air passage, an arm pivoted to the third named valve, means controlled by movement of said arm to adjustably limit the lift of the air valve, a member for operating said arm, and means adjustably fastening the operating 55 member to the third named valve.

2. In combination, a carbureting chamber, an air passage in the carbureting chamber, a fuel supply tube terminating in the air passage, a draft-operated valve for the air 60 passage, a needle valve for the fuel supply tube operative by movement of said draft-operated valve, another valve for the air passage having holes therein, a spring member having one end bent, means to pivotally hold

said spring member with its bent end in engagement with any one of said holes, and means operative by adjustment of the spring member for engaging another of said holes to adjustably limit the lift of the air valve. 65

3. In combination, a carbureting chamber, 70 an air passage extending into the mixing chamber, a fuel supply tube having its discharge end in the air passage, a homogenizing chamber fastened to the lower end of the carbureting chamber and surrounding the 75 lower end of the fuel supply tube, a second tube surrounding the lower end of the fuel supply tube and terminating at its upper end in a conical portion extending to the wall of the gasifying chamber, a mantle of 80 woven fabric on the outside of the first named tube, a mantle of woven fabric on the inside of the second tube, and a mantle of woven fabric on the outside of the second tube. 85

4. In combination, a carbureting chamber, an air passage opening through the wall of the carbureting chamber, a valve to control air entering the inlet end of the air passage, a draft-operated valve to control the passage 90 of air from the air passage to the carbureting chamber, a fuel supply tube having its discharge end in the air passage, a valve in the fuel supply tube operated by movement of the draft-operated valve, a cam operative 95 by movement of the first named valve, and a lever having one end arranged to limit the lift of the draft-operated valve and having its other end extending adjacent the face of the cam. 100

5. In combination, a carbureting chamber, an air passage opening through the wall of the carbureting chamber, a draft-operated valve to control the passage of air from the air passage to the carbureting chamber, a 105 fuel supply tube having its discharge end in the air passage, a valve in the fuel supply tube operated by movement of the draft-operated valve, means to limit the lift of the draft-operated valve, and a cam operative to 110 adjust the limiting means, said cam having an adjustable face whereby the lift of the draft-operated valve may be varied.

6. In combination, a carbureting chamber, a homogenizing chamber fastened to the lower end of the carbureting chamber, and a tube inside of the homogenizing chamber terminating at its upper end in a conical portion extending to the wall of the homogenizing chamber. 115 120

7. In combination, a carbureting chamber, an air passage in the carbureting chamber, a fuel supply tube having its discharge end in the air passage, a homogenizing chamber fastened to the lower end of the carbureting chamber and surrounding the fuel supply tube, a second tube surrounding the fuel supply tube and terminating at its upper end 125

- in a conical portion extending to the wall of the homogenizing chamber, and a mantle of woven fabric on the outside of the first named tube.
5. 8. In combination, a carbureting chamber, an air passage extending into the mixing chamber, a fuel supply tube having its discharge end in the air passage, a homogenizing chamber fastened to the lower end of the carbureting chamber and surrounding the lower end of the fuel supply tube, a second tube surrounding the lower end of the fuel supply tube and terminating at its upper end in a conical portion extending to the wall of the gasifying chamber, a mantle of woven fabric on the outside of the first named tube, and a mantle of woven fabric on the inside of the second tube.
10. 9. In combination, a carbureting chamber, an air passage in the carbureting chamber, a fuel supply tube terminating in the air
15. passage, a draft-operated valve for the air passage, a needle valve for the fuel supply tube operative by movement of said draft-operated valve, another valve for the air passage, a cam-carrying member adjustable relative to the last named valve, a cam member adjustably mounted on the cam-carrying member, and means connecting the cam to the draft-operated valve to limit the lift of said valve.
20. 10. In combination, a carbureting chamber, a homogenizing chamber, a tube in the homogenizing chamber communicating with the carbureting chamber, and a mantle of woven fabric supported by said tube.

Signed at Los Angeles, California, this 21st day of March, 1916.
